UNITED STATES PATENT OFFICE.

WILLIAM S. COOK, OF PARKERSBURG, WEST VIRGINIA.

INSULATOR.

Application filed October 9, 1923. Serial No. 667,550.

My present invention relates to electrical power transmission and more particularly to high tension insulators of the type used to support line wires. These insulators are usually pin type insulators that is porcelain insulators supported on a pin. They are usually composed of two or more parts or sections cemented together and my present invention has for its object to improve the method of cementing or joining these parts together with the object of rendering the joint firm but sufficiently elastic to take care of relative differences in the expansion of the parts under changing weather conditions. To these and other ends the invention resides in certain improvements and combinations of parts all as will be herein-after more fully described, the novel features being pointed out in the claims at the end of the specification.

In the drawings:

The figure is a sectional view of a pin type insulator constructed in accordance with and illustrating one embodiment of my invention.

Similar reference numerals throughout the several views indicate the same parts. I have illustrated in the drawing a familiar form of high tension pin type insulator to the assembling of which my improvements are particularly applicable. It comprises an upper or cap piece 1 having a groove or saddle 2 on its top to receive and support the line wire or conductor together with a lower or body section 3 having a socket 4 to receive the supporting pin. The cap section 1 is provided on its under side with a central cup shaped cavity 5 that is adapted to receive the similarly formed top 6 of the body section which fits it not too closely in order to leave the two surfaces slightly spaced and form a cavity for the bonding medium at the sides. The lateral outer walls of the portion 6 of the body member are provided with circumferential ribs 7 giving it a wave like contour in a longitudinal direction while the inner lateral walls of the cavity 5 of the cap section are similarly shaped to conform thereto in a reciprocal manner so that the one part may be inserted in the other with sufficient clearance but the final resulting space between the two will be substantially uniform.

When the parts are brought together in assembling, both the lateral and bottom walls of the cavity 5 of the cap piece 1 are

coated with a quantity of adhesive or quick setting cement as indicated at 8 and 9. The opposed walls of the top 6 of the body section 3 are also similarly coated as indicated at 10, the top of the body section and the bottom wall of the cavity being in contact except for the interposed body of adhesive 9. These coatings may be applied by dipping the body section and by painting the interior of the cap section or otherwise as may be most convenient.

After the application of the coating, the two parts are assembled in the relationship shown in which case of course permanent contact is made at the bottom of the cavity with the top of the body section and an annular space is left between the lateral walls of the two sections and between the coatings 8 and 10 thereof. The next step is to apply a body of hard or slow setting cement such as the Portland cement ordinarily used in such cases in this space. For this purpose, the parts are preferably inverted and a body 11 of the hard cement is poured into the bottom of the annular space. Next a layer of asphaltum or elastic cement 12 is spread upon the top (ultimately the bottom) of the body 11. Then another body 13 of the hard cement is applied succeeded by a layer 14 of asphaltum on top of which a final body of hard cement 15 is deposited.

I have referred to the elastic or quick-setting cement as asphaltum for the reason that this material is particularly adapted for such use. It may be applied while melted by heat and sets sufficiently when cooled.

The structure above described and the method of cementing locks the two parts of the insulator securely against relative disengagement with a positiveness contributed by the hard or slow-setting cement and yet with a certain elasticity contributed by the elastic or quick-setting cement, while both materials have high insulating value. The last mentioned function of elasticity prevents differential expansions and contractions of the two elements from setting up strains that endanger either the joint itself or the insulator structure as a whole which relative movements of the insulator parts, due to conditions of atmosphere or temperature are well known to those skilled in the art. The laminated or interspersed formation of the cemented joint and the two components thereof gives an opportunity for one part of

the insulator to expand or contract relatively to the other in any direction, that is vertically or longitudinally of the supporting pin as well as laterally.

5 I claim as my invention:

1. A two part insulator of the class described comprising cooperating respectively projecting and recessed parts secured together by lining and covering the walls of 10 both parts with an elastic cement there being provided intervening bodies of hard

cement and longitudinally spaced bodies of elastic cement interspersed therebetween.

2. A method of assembling two part insulators of the character described which 15 comprises coating the walls of cooperating projecting and recessed parts with an elastic adhesive and then pouring into the space between the walls alternate bodies of hard and of elastic cement.

WILLIAM S. COOK.
